(57) **CLAIM**

The ornamental design for a toy target, as shown and described.

DESCRIPTION

FIG. 1 is a front perspective view of a toy target, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1; and, FIG. 10 is an enlarged detail view of area 10 in FIG. 2.

The broken lines in the drawings illustrate portions of the toy target, which form no part of the claimed design. The dash-dot-dash broken lines shown in FIGS. 1, 2, 9 and 10 are for the purposes of disclosing areas of enlargement that form no part of the claimed design.
